J. S. Royce of Cuylerville N.Y.
Letters Patent No. 335. Dated Nov. 19. 1850.

The Schedule referred to in these Letters Patent and making part of the same.

To all whom it may concern:

Be it known that I, John S. Royce of Cuylerville in the County of Livingston and State of New York, have invented and produced a new and original design, being a metallic Plate for the side of a Carriage body and I do hereby declare that the accompanying drawing does clearly represent the shape of the said plate and the ornamental relief configurations upon the same.

My ornamental carriage body plate is represented in the accompanying drawing as attached to and making part of the body of a Buggy wagon, in which the part between B & C is intended for the support of the seat. The plate extends in an irregular curve from B to A to which latter point the dasher is attached. The part B. C. is ornamented by a representation of a spread Eagle holding in its talons the branch of a tree extending on either side with foliage & scroll work upon the edges. On the part from A to B, which sustains the floor of the wagon is represented the head and body of a serpent, the tail of which is intermingled with the foliage near the bend in the plate at B.

What I claim as my invention and desire to secure by Letters Patent is my design for an ornamental Carriage plate for the side of a wagon body, substantially in the manner herein set forth.

The above specification of my Design for an ornamental wagon plate signed & witnessed this 4th day of October 1850.
